ARCH SUPPORTING APPARATUS

Alexander E. Block, University City, Mo.

Application November 17, 1934, Serial No. 753,465

17 Claims. (Cl. 36—71)

This invention relates to shoes of the type that are equipped with removable or adjustable pads, inserts or cushioning devices which are adapted to be arranged in various positions for correcting or assisting in the treatment of various foot diseases or ailments.

One object of my invention is to provide a shoe of the general type mentioned, that is compact, light in weight, inexpensive to construct and equipped with a plurality of metatarsal arch pads and longitudinal arch pads that are positioned in pockets of novel construction and arrangement.

Another object is to provide a shoe of the general type mentioned, in which the holding means or retaining means for the removable pads is formed from pieces of relatively thin, flexible sheet material, such as leather or fabric, connected together in such a way as to form metatarsal arch pad pockets of novel arrangement whose rear ends are open, and longitudinal arch pad pockets having side openings, thereby enabling the shoe to be worn comfortably without the pads, due to the fact that the pad holding means is thin enough or flat enough to cause no annoyance or discomfort to the user when the pads are not in operative position.

Another object is to provide a shoe that is equipped with a metatarsal arch pad and a novel holding or retaining pocket for said pad, constructed so that the pad is accessible from the rear end of the pocket and is capable of being adjusted in an extreme forward position, wherein the pocket acts as an abutment to limit the forward movement of the pad and hold the pad so that a portion of same extends beyond the front end of said pocket, thereby enabling the shoe to be used to cure, correct or relieve metatarsal arch trouble that cannot be successfully handled with shoes or arch supporting apparatus of conventional construction.

And still another object of my invention is to provide a shoe that is equipped with a novel heel pad pocket and also with a heel pad of novel construction. Other objects and desirable features of my invention will be hereinafter pointed out.

I have herein illustrated my invention embodied in a shoe, but I wish it to be understood that my invention is applicable to arch supporting apparatus of the type that are adapted to be removably mounted in a shoe and also arch supporting apparatus of the type that are adapted to be inserted in a shoe and held in position on the inner sole of the shoe by an adhesive or other

suitable retaining means. The term "pad", as herein used, is intended to refer to and include any kind of a device or element that is used to cushion, support, treat, or provide comfort for a part or portion of the human foot.

Briefly described, my invention consists of a shoe provided with a pad carrier or holding means connected to the inner sole of the shoe, and constructed from pieces of relatively thin, flexible sheet material, such as leather or fabric; one or more pockets at the forward end of said carrier accessible from the top side of same and adapted to receive one or more metatarsal arch pads; one or more longitudinally-disposed pockets accessible from the top side of said carrier and adapted to receive one or more longitudinal arch pads; and a rear end pocket on said carrier accessible from the top side of same and adapted to receive a heel pad. Said carrier is preferably provided with a plurality of metatarsal arch pad pockets arranged in overlapping relationship and having their rear ends open so as to permit the metatarsal arch pads to be easily introduced into their pockets, and the longitudinal arch pad pockets have side openings through which the longitudinal arch pads may be easily introduced into said pockets. Due to the fact that the various pockets above referred to are formed from pieces of thin, flexible sheet material, the carrier, as an entirety, is relatively thin and will lie flat against the inner sole of the shoe without causing annoyance or discomfort to the user, if no pads are mounted in the pockets of the carrier. The metatarsal arch pads may be constructed in various ways and made of various shapes, but I prefer to use rubber or other soft material, and construct each in the form of a substantially feather-edged element of approximately disk shape, provided on one side with a flat face and on its opposite side with a convex surface having an eccentrically-disposed hump, a metatarsal arch pad of this particular form being capable of a multitude of adjustments, owing to the fact that it may be turned end for end or turned upside-down. The longitudinal arch pads may also be of various shapes and constructed of various materials. In the preferred form of my invention herein illustrated the shoe is provided with a single outer longitudinal arch pad that is substantially wedge-shaped in transverse cross section, and a plurality of inner longitudinal arch pads arranged end to end, in overlapping relationship, and each being of substantially wedge-shape in cross section. The pockets for the metatarsal pads, in addition to being arranged in

overlapping relationship, are so disposed with relation to the pockets for the longitudinal arch pads that one or more of the metatarsal arch pads can be adjusted or arranged so as to overlap 5 one or more of the longitudinal arch pads. The pockets for the inner and outer longitudinal arch pads are also preferably arranged in overlapping relationship, and the rear end portions of the pockets for the outer longitudinal arch pad and 10 one of the inner longitudinal arch pads extend over or are in overlapping relationship with the pocket for the heel pad. In using the shoe one or more of the pads previously referred to is arranged in the carrier or pad holding means, depending upon the particular kind of foot trouble 15 of the user, and after the trouble has been corrected or remedied, the pads may be removed from the carrier so that the carrier will lie flat upon the inner sole of the shoe.

20 Figure 1 of the drawings is a top plan view, partly broken away, of a shoe embodying my present invention.

Figure 2 is a vertical longitudinal sectional view, taken on the line 2—2 of Figure 1.

25 Figure 3 is a perspective view of the carrier or pad holding means with no pads arranged in same.

Figure 4 is a top plan view of the outer longitudinal arch pad.

30 Figure 5 is a top plan view of one of the metatarsal arch pads.

Figures 6 and 7 are top plan views of the two inner longitudinal arch pads.

Figure 8 is a perspective view of the heel pad.

35 Figure 9 is a perspective view of the removable insert of the heel pad.

Figures 10 and 11 are transverse sectional views, taken on the lines 10—10 and 11—11, respectively, of Figure 3.

40 Figure 12 is another perspective view of the carrier or pad holding means, showing the openings of the pockets in said carrier which are adapted to receive the inner longitudinal arch pads.

45 Figure 13 is a vertical transverse sectional view, taken through the heel portion of the shoe, showing the longitudinal arch pads removed from the carrier and the heel pads arranged in operative position.

50 Figure 14 is a view similar to Figure 13, showing the heel pad removed and the outer longitudinal arch pad arranged in operative position in the carrier.

Figure 15 is a similar view, showing the heel 55 pad removed and one of the inner longitudinal arch pads arranged in operative position.

Figure 16 is a vertical transverse sectional view, taken through the instep portion of the shoe, showing the carrier equipped with only one 60 longitudinal arch pad, i. e., the inner longitudinal arch pad that lies directly behind the metatarsal arch pads.

Figure 17 is a fragmentary top plan view, illustrating another adjustment of the metatarsal 65 arch pads; and

Figure 18 is a transverse sectional view, taken on the line 18—18 of Figure 17.

In the drawings 1 designates the inner sole of 70 my improved shoe which is equipped with an arch supporting apparatus, preferably built into the shoe so as to form an integral part of same. Said apparatus comprises two metatarsal arch pads A and A', an outer longitudinal arch pad B, two inner longitudinal arch pads C and C', a heel pad D, and a carrier or pad holding means,

designated as an entirety by the reference character x in Figure 3, provided with pockets in which said various pads are positioned. As shown in Figure 3, the carrier x is provided at its front end with two overlapping pockets 2 and 2^a that are adapted to receive the metatarsal arch pads A and A', respectively, a longitudinally-disposed pocket 3 that is adapted to receive the outer longitudinal arch pad B, two pockets 4 and 4^a (see Figure 12) that are adapted to receive the inner longitudinal arch pads C and C', respectively, and a rear end pocket 5 that is adapted to receive the heel pad D. As shown in Figs. 3, 10 and 12, and as hereinafter more fully explained the heel pad pocket 5 extends unbrokenly across the entire transverse width of the inner sole, said pocket being formed by a stationary base piece and a movable top piece whose front end is secured to the carrier by a transverse hinge or joint so that when the rear end of said top piece 20 is lifted or swung upwardly, a space is formed corresponding in width to the transverse width of the heel portion of the inner sole, in which a heel pad can be positioned. The carrier x is preferably made from a plurality of shaped pieces of thin, flexible sheet material such as leather or fabric, connected together by stitches y and permanently attached to the inner sole 1 of the shoe, as, for example, by means of a transversely-disposed curved row of stitches z, 30 as shown in Figures 1 and 2, the portion at the rear end of said carrier which constitutes the bottom of the heel pad pocket 5 being also preferably attached to the heel portion of the inner sole 1, as, for example, by the clinched or turned over upper ends of the nails 6 used to attach the heel 7 of the shoe to the outer and inner soles of the shoe. In order to protect the user's hose from direct contact with the pads or pad carrier, said carrier is provided with a sock liner or top 40 piece 8 whose front end is secured by the transverse row of stitches z, previously mentioned, the rear end portion of said sock liner or top piece 8 being free or unattached, so that said top piece may be lifted when it is desired to adjust or rearrange one or more pads of the apparatus.

The metatarsal arch pads A and A' are preferably of the form shown in Figure 5, each of said pads consisting of a feather-edged element, constructed of rubber or other suitable material, and provided with a flat bottom face and a concaved top face having an eccentrically-disposed hump 9, as shown more clearly in Figures 5 and 18. One end of said element is tapered, and at the opposite end of said element is a tang or reduced portion 10 which is used to hold the pad in adjusted position in its pocket. Thus, as shown in Figures 3 and 12, the top piece of each metatarsal arch pad pocket is provided with a flap or reduced extension having a plurality of transversely-disposed slits 11 that are adapted to receive the tang or reduced portion 10 at the rear end of the pad positioned in said pocket. To position either of the metatarsal arch pads, the pad is introduced into the rear end of its pocket, and after it has been set in the correct position, the tang 10 of the pad is inserted in one of the slits 11 in the flap on the top piece of the pocket, thereby causing the pad to be interlocked with the top piece of its pocket in such a way that it is effectively held against accidental shifting. In order to increase the range of adjustment of the metatarsal arch pads one or both of the pockets at the forward end of the carrier x may have its top piece cut away, as, for example, at 75

12, as shown in Figures 3 and 1. This cut away portion 12 of the top piece of the pocket is of less length than the width of the opening at the rear end of the pocket through which the pad is introduced into the pocket thereby permitting the pad in said pocket, for example, the pad A' to be adjusted forwardly into a position where the front end of the pocket acts as an abutment to limit the forward movement of the pad and the tapered front end of the pad projects forwardly beyond the front end of the pocket, as shown in Figure 1. By constructing the shoe in this manner I am able to arrange the metatarsal arch correcting means in a further forward position than would be possible if the pocket 2^a for the pad A' were provided with an imperforate or uncut front end, and I obtain a pocket in which the pad can be positioned quickly and easily due to the fact that the pocket 20 is provided at its rear end with an entrance opening of greater width than the extreme width of the pad and is provided at its front end with an opening (formed by the cut away portion 12) that is of less width than the extreme width of the pad. The metatarsal arch pad pockets 2 and 2^a are arranged in overlapping relationship, as shown in Figure 18, and said pockets are also preferably arranged in arcuate alignment, as shown in Figure 1, so as to permit the user to 30 arrange the pads A and A' so they will conform accurately to the anterior metatarsal arch. The portion of the carrier x that forms the base piece of the pockets for the metatarsal arch pads projects slightly beyond the front ends of the top 35 pieces of said pockets, and the front end of the sock liner 8 projects slightly beyond the terminal end of said base piece and is skived or feather-edged, so that there will be no transverse ridge on the inner sole of the shoe that might cause 40 annoyance to the user. Although the rear end portion of the carrier x that constitutes the base piece of the heel pad pocket 5 is secured to the inner sole of the shoe, as previously explained, the top piece of said heel pad pocket is free to 45 move upwardly to facilitate the introduction, removal, or adjustment of the heel pad, said heel pad pocket top piece being stitched or secured in the zone of the shank of the shoe at a point in front of the heel. Moreover, when the top piece 50 of the heel pad pocket is raised, the pockets for the longitudinal arch pads are brought into a condition which makes it very easy to insert, remove or adjust the longitudinal arch pads, this, of course, resulting from the fact that the 55 freely movable top piece of the heel pad pocket carries or is attached to portions of the carrier x which constitute parts of the pockets for the longitudinal arch pads.

The outer longitudinal arch pad B and the rear 60 inner longitudinal arch pad C are preferably made of cork, and as previously stated, are wedge-shaped in transverse cross section. The other longitudinal arch pad C' is preferably made of rubber and consists of an elongated member having one substantially semi-circular-shaped or segmental-shaped edge, and also a convexed surface that has an eccentrically-disposed hump 9^a, as shown in Figure 7. Due to the fact that the longitudinal arch pads and the metatarsal arch pads 65 may be arranged in overlapping relationship, and some of said pads may also be reversed or turned upside down, the apparatus may be adjusted so as to adapt itself to practically any human foot. This, coupled with the fact that the pads may 70 be adjusted, re-arranged or removed by the user

without requiring the services of one skilled in the treatment of foot trouble, makes the shoe a decided improvement upon prior arch supporting apparatus of the kind now on the market. Also, as previously stated, the carrier or pad holding means x of the shoe is of such construction that when it is not equipped with pads, said carrier will lie flat against the inner sole of the shoe, and thus not cause annoyance or discomfort to the user.

If it is necessary or desirable to use a heel pad, any suitable type or kind of heel pad may be arranged in the heel pad pocket at the rear end of the carrier x. I prefer, however, to equip the shoe with a heel pad that can be adjusted so 15 as to raise or lower the base of the user's heel bone or provide a hard or soft supporting surface for said heel bone. In the form of my invention herein illustrated, the heel pad D comprises a body portion 13 made of rubber and provided at 20 its center with a socket or depression 13^a in which a removable insert 14 is adapted to be positioned. The insert 14 is formed of material that is of a different character or nature than the material of which the body portion 13 of the heel pad is 25 constructed. For example, the insert 14 may be formed of material that is denser or slightly harder than the body portion of the heel pad, so as to form a support for the base of the heel bone that will not yield or compress as readily as the body 30 portion of the heel pad. If a higher or lower supporting surface for the base of the heel bone is required, this adjustment can be made by removing the insert and substituting for same an insert of proper height or thickness. As previously explained, the pocket 5 in the carrier that is adapted to receive the heel pad D, is accessible from the top side of the carrier, it being possible to introduce the heel pad into its pocket, simply by raising the rear end portion of the carrier 35 which constitutes the top part of the pocket 5 and then position the heel pad D on the bottom piece of said pocket that is attached to the heel portion of the inner sole 1 of the shoe.

As previously stated, my invention is applicable 40 to a shoe having an arch supporting apparatus of the kind above described, built into the shoe, and it is also applicable to an arch supporting apparatus built in the form of a unit or structure that is adapted to be removably mounted in a 45 shoe. In addition to being easy to adjust and providing an exceptionally large number of adjustments for the bones constituting the anterior metatarsal arch, the longitudinal arches and the heel, the apparatus is light in weight, inexpensive 50 to construct, and of such design that the carrier or pad holding means of same will cause no annoyance or discomfort to the user, in the event 55 said carrier remains in the shoe with no pads positioned in same.

Having thus described my invention, what I 60 claim as new and desire to secure by Letters Patent is:

1. A shoe having an arch supporting apparatus, comprising a carrier provided with pockets for longitudinal arch pads and a plurality of individual metatarsal arch pads on said carrier arranged in overlapping lateral relationship with one another and also disposed in overlapping relationship with one or more of the longitudinal arch 65 pads, thereby enabling a metatarsal arch pad to be arranged in various positions transversely of the carrier without liability of shifting laterally out of adjusted position.

2. A shoe of the kind described in claim 1, in 70

which the metatarsal arch pad pockets of the carrier are arranged in arcuate alignment.

3. A shoe of the kind described in claim 1, in which the carrier is formed from pieces of thin, flexible sheet material combined so as to form pad receiving pockets accessible from the top side of the carrier, the pockets for the metatarsal pads having slitted flaps that are used to hold the metatarsal pads in adjusted position.

10 4. A shoe provided with a pad carrier, formed from relatively thin, flexible sheet material, a pocket at the forward end of said carrier having an entrance opening presented toward the heel portion of the shoe, a longitudinally adjustable metatarsal arch pad positioned in said pocket, a slitted flap on the top wall of said pocket, and a part on the pad adjustably connected with said slitted flap.

5. A shoe provided with a pad carrier, formed from relatively thin, flexible sheet material, a pocket at the forward end of said carrier having an entrance opening presented toward the heel portion of the shoe, a longitudinally adjustable metatarsal arch pad positioned in said pocket, 20 with a portion of said pad engaging the front end of said pocket and a portion of said pad projecting forwardly through an opening in the front end of the pocket, and an integral portion on said pad adjustably interlocked with an integral portion of the top piece of said pocket.

30 6. A shoe provided with a pad carrier constructed from relatively thin, flexible sheet material, a plurality of individual metatarsal arch pad pockets on the upper side of the front end portion of said carrier arranged in overlapping lateral relationship and in arcuate alignment, the rear ends of said pockets being open and the top pieces of said pockets having flaps, and adjustable metatarsal arch pads removably mounted in said 35 pockets and adjustably connected with said flaps, one of said pockets having an opening in its front end so as to permit the pad in said pocket to be adjusted into a position where a portion of said pad projects forwardly through said opening and 40 a portion of said pad engages the front end of the pocket.

45 7. A shoe of the kind described in claim 6, in which said pads are provided with tangs and the top piece of each of said pockets is provided with a plurality of transversely-disposed slits in its flap located different distances from the front ends of said pockets and adapted to receive the tangs on said pads.

50 8. A shoe provided with a pad carrier formed from a plurality of pieces of relatively thin, flexible sheet material connected together in such a way as to form a heel pad pocket at the rear end of the carrier, a plurality of individual metatarsal arch pad pockets arranged in overlapping lateral relationship at the front end of the carrier, and intermediate pockets for receiving inner and outer longitudinal arch pads, said intermediate pockets having side openings and said end pockets having entrance openings at their rear ends, and 55 removable pads positioned in said pockets and adapted to be arranged so that the metatarsal arch pads may be arranged in overlapping relationship with one another and with two of the longitudinal arch pads and two of said longitudinal arch pads may be arranged in overlapping 60 relationship with the heel pad.

70 9. A shoe provided with a pad carrier, a removable heel pad in said carrier, and a removable in-

sert in said pad adapted to serve as a support for the base of the user's heel bone and formed from material that is of greater density or hardness than said pad.

10 10. An arch supporting apparatus for shoes, comprising a carrier, formed of relatively thin, flexible sheet material, said carrier being adapted to be permanently attached to the inner sole of a shoe and provided with a plurality of pockets accessible from the top side of said carrier, reversible metatarsal arch pads arranged in overlapping relationship at the front end of said carrier, a removable heel pad at the rear end of said carrier, provided with a central portion that may be changed to vary the supporting surface for the user's heel bone, and adjustable, longitudinal arch pads of substantially wedge shape in cross section mounted on said carrier in overlapping relationship.

15 11. A heel pad for shoes provided with a portion adapted to serve as a support for the user's heel bone and being of greater density or hardness than the remainder of the pad.

20 12. A pad carrier for shoes, and a pad pocket on said carrier, said pocket having an opening 25 at its forward end, the front portion of the bottom of said pocket being stationary or immovable and the rear end portion of said pocket being slotted so as to hold inserts at various points with reference to the length of said pocket.

25 13. A pad carrier for shoes, provided with a base piece, a pad pocket on the anterior arch portion of the carrier, and a separate pad pocket on the rear portion of the carrier, the front end of said rear pocket overlapping the rear end of 30 the anterior arch pocket.

35 14. An adjustable inner longitudinal arch pad for shoes, consisting of an elongated member of substantially ellipsoidal form in general outline, that is adapted to be arranged with its long axis 40 extending longitudinally of the shoe, said member being provided on one of its surfaces with a hump disposed at one side of the longitudinal axis of said member.

45 15. An arch supporting apparatus for shoes, comprising a carrier adapted to lie upon the inner sole of the shoe and provided at its forward end with pockets for receiving metatarsal arch pads, said pockets having provision for holding the pads in overlapping lateral relationship and in 50 arcuate alignment, the rear ends of said pockets being open.

55 16. An arch supporting apparatus for shoes, comprising a base piece adapted to be attached to the inner sole of the shoe, a top piece adapted to be raised or lifted, and an intermediate portion between said top piece and base piece hinged at a point between the heel and the zone of the rear transverse arch area.

60 17. A pad carrier for shoes, comprising a base piece adapted to be anchored to the inner sole of a shoe, and superimposed portions on the top side of said base piece arranged in overlapping relationship and hinged to said base piece at different zones, said overlapping portions cooperating 65 with each other and with the base piece to form pad pockets accessible from the top side of the carrier and each comprising a flap or top part whose rear end can be raised to facilitate the insertion, removal or adjustment of the pads 70 in said pockets.

ALEXANDER E. BLOCK.
